(57) **CLAIM**

The ornamental design for an electronic cymbal, as shown and described.

DESCRIPTION

1. Electronic cymbal

1.1 : Perspective

1.2 : Front

1.3 : Back

1.4 : Left

1.5 : Right

1.6 : Top

1.7 : Bottom

1.8 Enlarged view taken from 1.2

1.9 Cross-sectional view taken along line 1.9-1.9 in 1.8

The dashed broken lines illustrate portions of the article that form no part of the claimed design. The dot-dash lines define boundaries of the claimed design that form no part thereof. The cross-sectional view taken along line 1.9-1.9 only shows the surface portion of this article. The dot-dot-dash broken lines depict reference to the enlargements shown in 1.2 and 1.8 and form no part of the claim.

1 Claim, 9 Drawing Sheets
